CLAIM

The ornamental design for a spice cup, as shown and described.

DESCRIPTION

FIG. 1 is a perspective view of a spice cup, with a portion of the sidewall cut out for ease of illustration to show a denesting lug within the spice cup.

FIG. 2 is a perspective view of a spice cup;

FIG. 3 is a front elevational view thereof;

FIG. 4 is a rear elevational view thereof;

FIG. 5 is a first side elevational view thereof;

FIG. 6 is a second side elevational view thereof;

FIG. 7 is a top elevational view thereof;

FIG. 8 is a bottom elevational view thereof;

FIG. 9 is a cross-sectional view thereof showing a section taken along line 9-9 of FIG. 7; and,

FIG. 10 is another cross-sectional view thereof showing a section taken along line 10-10 of FIG. 7.

The evenly spaced broken lines in the drawings are included for the purpose of illustrating portions of the spice cup that form no part of the claimed design. The dot-dash-dot broken lines in the drawings are included for the purpose of defining the boundary lines of the claim, it being understood that the claimed design lies between the boundary lines, it being understood that the dot-dash-dot broken lines themselves form no part of the claimed design.
